UNITED STATES PATENT OFFICE.

LOUIS EDWY BARTON, OF MALTA, ILLINOIS.

SNOW-PLOW.

1,269,367.

Specification of Letters Patent. Patented June 11, 1918.

Application filed March 18, 1918. Serial No. 223,413.

To all whom it may concern:

Be it known that I, LOUIS EDWY BARTON, M. D., a citizen of the United States, and a resident of the town of Malta, in the county of De Kalb and State of Illinois, have invented a certain new and useful Improvement in Snow-Plows; and I do hereby declare that the following description of my said invention, taken in connection with the accompanying sheet of drawing, forms a full, clear, and exact specification, which will enable others skilled in the art to which it appertains to make and use the same.

My invention relates generally to improvements in snow plows; and it consists, essentially, in the novel and peculiar combination of parts and details of construction, as hereinafter first fully set forth and described and then pointed out in the claims.

The object of this invention is the production of an efficient and serviceable snow plow, which though applicable to general use, is especially designed for country roads. In order to accomplish this object, I construct this snow plow, in the preferred embodiment of my invention, as shown in the drawings, in which—

Figure 1 is a side elevation of my snow plow as it appears when in actual use. Fig. 2 is a plan of the same. Fig. 3 is a plan of the sled and a part of the pushing device by which the sled is propelled and steered. Fig. 4 is a rear elevation of the snow plow proper, details of construction of the pushing mechanism being omitted. Fig. 5 is an elevation, partly in section, of mechanism for raising and lowering the rear end of the movable platform to change the inclination thereof. Fig. 6 is an elevation of this device as it appears when turned through an angle of 90 degrees. Fig. 7 is a plan of part of the pushing and steering mechanism detached. Figs. 8, 9, and 10, are further details in perspective, of this device.

Like parts are designated by the same characters and symbols of reference in all the various figures.

This snow plow comprises two main structures, viz. the snow plow proper A, and a sulky B, by which latter, and horses C, hitched thereto, the snow plow is propelled by pushing the same ahead.

The snow plow proper is comprised of 55 a frame structure consisting, preferably, of a pair of substantial runners 12, 13, which are connected by a series of transverse bars or rails 14, 15, 16.

Upon this frame structure, which is, preferably, constructed of wood, there is affixed a platform D, which inclines upwardly and rearwardly at an angle of 20 degrees, more or less. It traverses the frame structure and extends beyond the rear end thereof for some distance. Upon this fixed platform there is located a second platform E, of the same width as the fixed platform, but somewhat shorter than the latter. This second platform, which I shall hereinafter term the movable platform, is hinged or pivotally connected to the fixed platform at its forward end, a slight distance from the forward end of the fixed platform; strap hinges 17, or analogous means being employed for this purpose. The rear end of this movable platform E is supported by an elevating device F, of any approved design, an example of such a device being best shown in Figs. 5 and 6. It comprises, preferably, a rotatable screw 18, provided at its upper end with a hand wheel or other suitable means 19, which by a ball and socket joint 20, at the lower end of the screw, permits of the screw being rotated and rocked to adapt itself to different positions it may have to assume when rotated to raise or lower the movable platform.

Upon this screw 18 there is mounted a nut 21, which nut has trunnions 22, oscillatably mounted in bearings 23, fixed to the movable platform E, to accommodate itself to the inclination of the screw 18 with reference to the movable and fixed platforms. Rotating this screw in one direction will 95 cause the rear end of the movable platform to rise, while a contrary movement of the screw produces a corresponding reverse result.

Upon the movable platform there is located a structure G, which I shall hereinafter term the deflector, its object being to deflect snow rising on the movable platform from its rearward moving course, and to cause it to be discharged from the platform E at the sides of the runners 12, 13, of the plow proper. To this end the deflector comprises two triangular members 24, 25, Figs.

1, 2, and 4, jointed together angularly at the apex 26, to serve similar in action to a mold board of a plow, to elevate the snow and throw it off the movable platform. To the sides of the movable platform are hinged fenders 28, 29, preferably by strap hinges 30. These fenders are provided with means for changing their angularity with reference to the movable platform, an example 10 of such means being illustrated in Fig. 4. A strap 31, on each fender, is pivotally connected to the fender at 32, which strap has a series of notches 33, to engage a pin 34. This pin is placed into a U-shaped support 15 35, rising from the runners 12, 13, and supporting the fixed platform D near its rear end. By changing the notches in the straps 31, the fenders may be angularly adjusted to throw the snow descending from the deflectors farther away from the runners, or 20 dropping it nearer thereto, as the case may require, in an obvious manner.

The sulky B is of the usual two-wheels construction, and if desired, the rear axle 25 and wheels of an ordinary farm wagon, may be employed for the purpose of moving the snow plow proper. To the axle tree 36, Fig. 2, of this sulky there is affixed a rearwardly extending foot board 37, upon which the operator H, takes his position to guide the horses and to steer the machine. For this purpose of pushing and steering the plow, I employ peculiarly constructed mechanism, comprising a bar 38, located medially be- 30 tween the runners 12, 13, upon the cross rails 15, 16. This bar abuts with one end against a stop 39, Figs. 3 and 4, comprising, if desired, an iron angle bar; and this end of said bar 38 is, preferably cylindrical, as 35 indicated at 42, Fig. 7, and provided with a hole 40, in which there is a substantial pin 41, passing through the rail 15; the hole 40 being, preferably, oblong, as shown, the object of which will further on appear. This 40 bar 38 extends some distance beyond the rail 16, and it has near its outer end a further journal 42^a, embraced by a U-shaped strap 43, Figs. 3 and 4, secured upon the rail 16. This journal 42^a is transversely 45 slotted at 44, Fig. 7, to receive a pin 45, passing through the slot, the strap and the rail 16, as illustrated in Fig. 4.

At the sides of the bar 38 there are straps 46, best shown in Figs. 7 to 10 inclusive, a 50 pivot bolt 47, passing through these straps near the end of the bar 38, which end is, preferably, horizontally rounded off as indicated in Fig. 8 at 49. To these straps is bolted a short extension 38^a, of the bar 38, 55 and the outer end of this extension is vertically rounded off, as shown at 49^a, in Figs. 9 and 10.

The reach 51, of the sulky B extends forwardly and abuts against the rounded end 60 49^a of the extension 38^a, and connects with

the latter by two straps 50, placed on the upper and lower surfaces of the extension 38^a and the forward end of the reach 51; bolts 52, passing through the plates or straps 50, and the adjacent ends of the extension 70 38^a and the reach 51, being provided to make proper, flexible, connection.

In the bar 38, near its rear end, there is a vertically disposed bolt hole 53, in which there is mounted a bolt 54, Figs. 3 and 7, 75 and in the reach 51, near its forward end there is a bolt hole 55, in which is mounted a pivot bolt 56, on which there is fulcrumed a handle bar I, the forward end of which 80 engages the bolt 54, and the rear end of which reaches to within a convenient distance of the operator standing on the foot board 37.

The operation of this pushing and steering mechanism is substantially as follows: 85

The horses being properly hitched to the sulky and moving forward, causes the reach of the sulky to push against the extension 38^a, and this, in turn, pushes against the push-bar 38, and by it, move the snow plow 90 forwardly into the snow in front of the plow. This snow ascends the forward portion of the fixed platform (which has sharp-edges) and is deflected therefrom by the deflector and discharged from the fenders, as 95 already described. When it is desired to make a turn in the road, the operator moves the handle bar 51 in the proper direction. This handle bar is a long lever having its fulcrum in the pivot bolt 56, and its short 100 arm connected to the push bar 38 by the bolt 54. It follows that by this movement of the handle bar the rear end of the plow is deflected from a straight course, which movement the sulky will follow until the handle 105 bar is again brought in normal position or alignment with the reach 51. And in order that this reach 51 and the push bar 38 may readily assume this angular position, the end of the extension 38^a, or the forward end of 110 the reach (or both) is rounded off at 49.

In operating this snow plow over undulatory ground a condition may arise wherein the sulky and the plow may not be in the same horizontal plane which would cause 115 torsional stress in the reach or in the push bar 38. To avoid this objectional feature, I have provided the push bar 38 with the journals 42, 42^a, so that either the plow or the sulky may rotate or rock; and to permit 120 this rocking movement, the slots in the journals are provided for the reception of the pins 42 and 45. These pins, while not essential when the plow is being pushed, are, nevertheless, necessary when the plow is 125 backed up and the push rod 38 pulls on these pins. And in order that the snow plow may readily rise or fall to follow undulations of the ground over which the machine is being moved, I have provided the 130

push bar 38 with the extension 38^a, and have pivotally connected these two parts by the plates 46 and the bolts 47, and 48, which accomplishes the desired function in an efficient manner.

5 In some cases I may provide the adjacent ends of the reach 51 and the extension 38^a with a positively functioning connection, by supplying these ends with castings having segments of cog wheels 57, as shown in Fig. 10 7, whereby the angular movement of the reach and the push bar is greatly facilitated.

I may here state that while metal may be 15 largely employed in the construction of this snow plow, I prefer to construct the principal parts thereof of wood, it being a well-known fact that snow will readily adhere to metal when the latter is cold, and thereby 20 prevent rapid and efficient movement of the snow on the platforms, the deflectors, and the fenders. It is also desirable that when 25 an ice-crust has formed on the snow to be moved, this crust be broken; and for this purpose I mount on the forward ends of the runners vertically disposed knives 60, which will accomplish the desired function in a satisfactory manner. On country roads which have been covered with snow on 30 which there has been more or less traffic, so that the snow is packed and grooved or guttered by the runners of sleighs or by vehicle wheels and then more snow has fallen which it is necessary to remove to preserve this 35 thin, hard packed layer so that traffic with sleighs may be carried on, I have provided the snow plow with a pair of auxiliary runners 61, 62, spaced apart the usual spur width of a farm wagon or sleigh, which is 40 also the distance of the grooves or tracks in the snow. These two auxiliary runners are somewhat less in depth than the runners 12, 13, and when running in the guttered tracks prevent the snow plow from sinking deeper 45 into the snow than desired, thereby preserving a sufficiently deep snow-bed on the road to render traffic with sleighs, sleds, and cutters easily feasible, which would not be the case were all the snow on the road removed 50 by the plow. It will thus be noted that this snow plow is not necessarily designed to completely remove snow from streets or roads, but rather to leave thereon a layer of snow on which traffic with road vehicles is 55 possible.

I have hereinbefore stated that the snow plow is propelled by a team of horses, but it is evident that the propelling power may be other than animal power, such as traction engines, and the like.

60 I have hereinbefore described the preferred embodiment of my invention with considerable minuteness; but I desire it to be distinctly understood that I am aware that 65 changes in the details of construction dis-

closed may be made, and parts omitted without departing from the scope of my invention as defined in the subjoined claims.

Having thus fully described this invention, I claim as new and desire to secure to 70 myself by Letters Patent of the United States—

1. In a machine of the nature described, a snow plow proper, said plow consisting of a pair of principal runners, a pair of auxiliary runners intermediate the principal runners, the latter runners being of less depth than the principal runners, a fixed platform mounted on said runners in inclined position, a movable platform hingedly connected at its forward end to the forward end of the fixed platform, mechanism for raising and lowering the rear end of the movable platform, fenders hingedly connected to the movable platform at the side margins thereof, a 75 deflector on the movable platform, said deflector comprising two triangular members jointed together along one margin of said members, the margins of said members where they join the movable platform being angularly placed to resemble the letter "V," and means whereby said snow plow is 80 propelled, said propelling means being located in the rear of the machine.

2. In a machine of the nature described, 85 a snow plow proper, said plow comprising a pair of runners, a fixed platform mounted on said runners in inclined position, a movable platform hingedly connected at its forward end to the forward end of the fixed 90 platform, mechanism for raising and lowering the rear end of the movable platform, fenders hingedly connected to the movable platform at the side margins thereof, a deflector on the movable platform, said deflector comprising two triangular members jointed together along one of the margins of 95 said members, the margins of said members where they join the movable platform being angularly placed to resemble the letter "V," and means whereby said snow plow is 100 propelled, said means being located at the rear of the machine, said fenders being provided with means for changing their angularity with reference to the movable platform.

3. In a machine of the nature described, 105 a snow plow proper, said plow comprising a pair of runners, a fixed platform mounted on said runners, said fixed platform being 110 rearwardly and upwardly inclined, said platform being fixed to the runners at its forward end, an arched support upon said runners for the rear end of said fixed platform, a movable platform hingedly connected to 115 the forward end of the fixed platform, mechanism for raising and lowering the rear end of said movable platform, fenders hingedly connected to the movable platform at the side margins thereof, a deflector on the 120

movable platform, and means whereby said snow plow is propelled, said propelling means being located at the rear of the machine, said deflector including two triangular members jointed at one of their side margins and angularly disposed with reference to the plane of the movable platform, said fenders being provided with bars having a series of notches engaging pins for changing the angularity of said fenders with reference to the plane of the movable platform.

4. In a machine of the nature described, a snow plow proper, a sulky behind said snow plow, a push bar connected to said snow plow, a reach connected to said sulky, said reach and said push bar being link-connected, and a steering bar, said steering bar being fulcrumed to said reach and pivotally connected to said push bar to swing the rear end of said snow plow in one or the other direction when properly manipulated.

5. In a machine of the nature described, the combination, of a snow plow proper, of means whereby said snow plow is propelled, and means for steering the same, including a push bar connected to said snow plow, a reach connecting to said propelling means, a link connection between said push bar and said reach, a steering bar fulcrumed upon said reach and pivotally connected to said push bar, said push bar being provided with journals to permit said snow plow to rock

without imparting torsional stress to said push bar.

6. In a machine of the nature described, the combination, of a snow plow proper, of means whereby said snow plow is propelled, and means for steering the same, including a push bar connected to said snow plow, a reach connected to said propelling mechanism, a link connection between said push bar and said reach, a steering bar fulcrumed upon said reach and pivotally connected to said push bar, said push bar being provided with journals to permit said snow plow to rock without imparting torsional stress to said push bar, said push bar comprising two pivotally connected members, to permit rolling movement of said snow plow.

7. In a machine of the nature described, the combination, of a snow plow proper and means whereby said snow plow is propelled, said means including a push bar extending rearwardly from said plow, a wheeled vehicle at the rear of said plow, a reach connecting said wheeled vehicle to said push bar, a link connection between said push bar and said reach, the abutting ends of said reach and said push bar being provided with gear teeth.

In testimony that I claim the foregoing as my invention I have hereunto set my hand.

Dr. LOUIS EDWY BARTON.
